UNITED STATES PATENT OFFICE.

ALBERTO BALLOCO, OF TURIN, ITALY, ASSIGNOR TO ITALA FABBRICA DI AUTOMOBILI,
OF TURIN, ITALY.

DISTRIBUTER FOR INTERNAL-COMBUSTION ENGINES.

1,117,761.

Specification of Letters Patent.

Patented Nov. 17, 1914.

Application filed September 9, 1911. Serial No. 648,504.

To all whom it may concern:

Be it known that I, ALBERTO BALLOCO, a subject of the King of Italy, and residing at Turin, Italy, have invented certain new and 5 useful Improvements in Distributors for Internal-Combustion Engines, of which the following is a specification.

This invention relates to rotary distributors for internal engines and more particularly to a distributor cooled internally by the circulation of water.

In the accompanying drawing is shown, by way of example, a construction according to the invention.

15 Figure 1 is a section on line $x-x$ of Fig. 2, and represents two coupled cylinders to which the new type of rotary distributor is applied. Fig. 2 is a vertical section on a plane passing through the axis of one of the 20 cylinders and the distributor.

As will be seen from the drawings the distributor 1 consists of a cylindrical body mounted so as to turn on its axis in a chamber 2 adjacent to the engine cylinders this 25 rotation being transmitted to the body by the shaft 3 driven from the motor shaft at the desired relative speed. The chamber 2 is in communication with the ends of the cylinders through ports 4 and 5 and the distributor 30 has two channels 6 and 7 communicating respectively with the admission pipe 8 and with the exhaust pipe 9. The channel 6 extends for a portion of its length axially into the distributor and then it is bifurcated

35 into two channels leading to diametrically opposite points so as to form in the cylindrical wall of the distributor two openings intended to register with the ports 4 and 5 of the cylinders when the admission commences. Similarly, the channel 7 is composed of two branches leading to diametrically opposite points, the openings formed being intended to register with the ports 4 and 5 of the cylinders when exhaust commences.

40 The two branches of the channel 7 extend upward and are reunited in a chamber arranged at the upper part of the distributor and which is always in communication with the exhaust pipe 9. These channels are formed on the interior of the distributor by walls cast with the body of the distributor. Between the walls of these 45 channels and the outer cylindrical wall of the distributor there is a space surrounding

50 the various pipes and forming a channel

which commences at the upper part of the distributor, descends to the bottom and rises again to the top on the opposite side to pass out axially relatively to the distributor. Into this pipe water is introduced by means 60 of a pipe 10 entering axially and by reason of the vertical arrangement of the distributor the water introduced from above may circulate spontaneously on account of the difference of temperature and rise again 65 in the body of the distributor, passing off through the pipe 11 (see the arrows in Fig. 2).

In the case shown in the drawings, the engine being a four-stroke cycle engine, the distributor turns at a speed equal to one fourth of that of the engine so that each channel, both the admission channels 6 and the exhaust channels 7 which have two opposite ports, successively register with the 70 ports of the coupled cylinders being at an angular distance from each other of 45° . It is also possible by modifying the ratio of transmission between the engine shaft and the shaft 3 to increase the number of ports 75 of the distributing channels, it only being necessary that they shall register with the port of the cylinder at the moment when the corresponding phase begins in that cylinder.

80 For the purpose of balancing, during the compression and explosion periods, the pressure on the wall of the distributor which closes the port 4 or 5 of the corresponding cylinder, there are made in the wall of the chamber 2, two small cavities 12-13 opposite the ports of the cylinders. At the moment of compression and explosion there opens opposite these cavities the passage 14 which extends through the distributor so as to 85 form communication between one or other of the said cavities and the corresponding cylinder at the required moment. In this manner the distributor is subjected to the pressure existing in the cylinder at two 90 points diametrically opposite each other so that the operation will not be prejudiced by the friction between the walls of the distributor and of the chamber, caused by the pressure of the gases in the cylinder acting 95 in the distributor at opposite points. The tightness of the distributor is secured by elastic rings 15. By this mode of distribution there is obtained by means of a single member both the admission of the combus- 100

tible mixture and the exhaust for two or more cylinders under conditions such that the distributor is balanced and cooled by the circulating water.

5 What I claim as my invention and desire to secure by United States Letters Patent is:—

1. In a valve for internal combustion engines, the combination of a chamber communicating with the engine cylinders; a distributor in said chamber, rotatable about a vertical axis and provided with a channel passing therethrough and a channel for the cooling water, the last named channel commencing axially from above and descending nearly to the bottom and rising again to the discharge; and means for conducting the water to and from said named channel.
2. In a valve for internal combustion engines, the combination of a chamber communicating with the engine cylinders; a distributor in said chamber and rotating about a vertical axis; and provided with a channel passing therethrough for the hot gases, and a channel for the cooling water

surrounding the channel for the gases in such a manner that water introduced from above descends spontaneously to the bottom of the valve and then rises to the top; and admission and exhaust pipes for the distributor.

3. In a valve for internal combustion engines, the combination with the cylinders, of a chamber into which the ports of the cylinders open at diametrically opposite points; a distributor in said valve and rotatable about a vertical axis and provided with a channel passing therethrough and having branching upper end adapted to register with said ports, for the purpose of equalizing the pressure on the walls of the cylinder during the compression and explosion; and means for conducting cooling medium through the distributor.

40 In testimony whereof I affix my signature 45
in presence of two witnesses.

ALBERTO BALLOCO.
